CHARLES WILBERT UNKLE, OF BALTIMORE, OHIO.

APPARATUS FOR PAPER MANUFACTURE.

Application filed May 23, 1925. Serial No. 32,240.

The invention relates to the manufacture of paper and paper board and is particularly directed to processes of applying coloring material to the paper stock.

5 Heretofore, in the manufacture of paper and paper board, the practice has been to insert the coloring matter in the beater from which the paper forming material is passed through a series of chests into the jordan 10 and from the jordan it is pumped into a mixing tank from which the stock passes onto screens and into the machine vat or vats. All of the material flowing from the mixer to the machine vats is of the same 15 color hence but one color of paper product of a given furnish is possible unless the surface of the product is colored at the calender by special appliances. Where paper or paper board of the same furnish is desired 20 to be made in different colors it has been possible to produce but one color of product at a time by the unit above described, excluding the coloring at the calenders.

The object of my invention is to provide 25 an organization whereby a plurality of papers or paper boards differing in their color may be made simultaneously from a stock originating at a common source.

I have found that by forming compartments in the mixing tank or chest and connecting each compartment to a unit of screens and machine vat that one coloring material may be inserted into one compartment, another color in another compartment 35 and so on, the stock discharging from each compartment having the desired color so that a variety of colored paper or paper board of the same furnish may be made from stock prepared in one beater or one 40 ply of the paper board may have one color and another ply another color. This results not only in a large saving in time and appliances but a perfectly lined board or paper is formed in the selected color or colors.

45 In the accompanying drawing Figure 1 is an elevational view of part of the main elements in diagrammatic form of a system or organization for carrying out my invention, and Fig. 2 a plan view of the mixing 50 tank and machine vat.

In the drawings, 1 indicates the beater and 2 a chest that communicates through conduit 3 with the beater. A pump 4 elevates the stock that discharges from the beater 55 into the chest, into a second chest 5, from which the stock passes through a conduit 6

into a jordan 7. A pump 8 conveys the stock from the jordan into a chest 9 and elevates it through a conduit 10 into the mixing tank 11. The conduit 10 is preferably 60 connected to one side 12 of the tank 11.

A baffle 13 extends downwardly in the tank between its end walls, the lower edge of the baffle being spaced from the bottom of the tank, and between this baffle and the opposite side 14 of the tank is a partition 15 extending from end to end of the tank and from the bottom to the top thereof. The space between the partition 15 and the side wall 14 of the tank is divided by cross-partitions 16 into compartments A, B, C, or such number of compartments as there may be cylinders on the paper machine. Apertures 17 are formed in the partition 15 to form independent communications between 70 each compartment and the main portion D of the tank. These apertures are controlled by suitable gates or valves 18. Conduits 19, 20 and 21 communicate with the compartments A, B and C respectively and each 80 conduit leads to a screen or screens 22, the latter communicating with a chest 23 and the chest communicating through the pipe 23^a with the cylinder compartment C' of the machine vat 24, the other compartments A 85 and B having similar connection with the cylinder compartments A' and B' of the machine vat.

The paper forming material is inserted in the beater for the usual treatment, the stock 90 formed therein passing through the several chests and the jordan in the usual manner and for the usual purpose, and it eventually flows into the compartment D of the mixing tank. From this compartment the 95 stock flows into the compartment A, B, C or such of them or such others which may be provided, as the operator chooses. The coloring materials are added to the stock in these compartments A, B, C, and since 100 there is no communication between those compartments after the gates are closed, one color may be added to compartment A, another to compartment B, and another to compartment C, and so on, so that the uncolored stock entering the compartment D may discharge from the several compartments A, B, C, in independent conduits each stream of stock being colored differently than the others.

105 A three cylinder paper machine, for example, may thus produce simultaneously

paper or paper board of a selected furnish in three different colors. When a change in color is desired it is only necessary to flush out the particular compartment A, B or C 5 and the devices beyond it and having communication with it.

It is thus apparent that by my method a variety of coloring material may be independently applied to a given quantity of 10 stock of a selected furnish and thereby simultaneously produce finished products of different colors.

What I claim is:

1. In a paper making machine, a mixing 15 tank, a partition extending across the mixing tank and dividing the same into a receiving end and a discharge end, other partitions dividing the discharge end of the tank into a plurality of compartments, the 20 first mentioned partition having a plurality of gate control openings corresponding in number to said compartments and each communicating with a respective compartment, a plurality of conduits leading individually 25 from respective compartments, a baffle extending downwardly in the tank in spaced relation to the first partition and terminating in spaced relation to the bottom of the tank, said baffle being located in the receiving 30 end of the tank, and a conduit communicating with the receiving end of the tank at the side of the baffle remote from the first partition.
2. In a paper making machine, a mixing 35 tank, a partition extending across the mixing tank and dividing the same into a receiving end and a discharge end, other partitions dividing the discharge end of the tank into a plurality of compartments, the 40 first mentioned partition having a plurality

of gate control openings corresponding in number to said compartments and each communicating with a respective compartment, and a plurality of conduits leading individually from respective compartments; in combination with a machine vat having a plurality of compartments equal in number to the compartments formed in the delivery end of the mixing tank, each of the first mentioned conduits communicating with a 50 respective compartment in the machine vat.

3. In a paper making machine, a mixing tank, a partition extending across the mixing tank and dividing the same into a receiving end and a discharge end, other partitions dividing the discharge end of the tank into a plurality of compartments, the first mentioned partition having a plurality of gate control openings corresponding in number to said compartments and each communicating with a respective compartment, a plurality of conduits leading individually from respective compartments, a baffle extending downwardly in the tank in spaced relation to the first partition and terminating in spaced relation to the bottom of the tank, said baffle being located in the receiving end of the tank, and a conduit communicating with the receiving end of the tank at the side of the baffle remote from the first partition; in combination with a machine vat having a plurality of compartments equal in number to the compartments formed in the delivery end of the mixing tank, each of the first mentioned conduits 60 communicating with a respective compartment in the machine vat.

In witness whereof I hereunto sign my name this 21st day of May, 1925.

CHARLES WILBERT UNKLE.
